UNITED STATES PATENT OFFICE.

FERDINAND O. SPAULDING, OF FAIRFIELD, MAINE.

DUST-PAN.

1,270,340.

Specification of Letters Patent. Patented June 25, 1918.

Application filed February 23, 1917. Serial No. 150,509.

To all whom it may concern:

Be it known that I, FERDINAND O. SPAULDING, a citizen of the United States, residing at Fairfield, in the county of Somerset and 5 State of Maine, have invented certain new and useful Improvements in Dust-Pans, of which the following is a specification.

This invention relates to dust pans and the primary object of the invention is to 10 provide an improved utensil of this character that will be more efficient than the ordinary dust pans now generally used and one which can be constructed from a single 15 piece of material which may be folded for providing the necessary parts for performing the functions pertinent to the device.

One of the objects of the invention is to provide a receptacle for the dirt and dust swept upon the pan whereby accidental 20 placement of the contents of the receptacle will be prevented by its construction with respect to the angular disposition of the dust pan blade.

A further object of the invention is the 25 provision of means for ejecting the contents of the receptacle in a manner that will permit the dirt and dust which comprises the contents to be concentrated at one point of ejection so that spreading of the dirt and 30 dust will be prevented.

Another object of the invention resides in the provision of a thoroughly braced dust pan of this character that will possess the 35 rigidity for the purpose of avoiding distortion of the blade without the use of additional braces or reinforcing members.

A further object of this invention is the 40 provision of a dust pan which consists of comparatively few parts and is simple in construction, but durable and well adapted to withstand the rough usage to which devices of this character are ordinarily subjected.

For a full description of the invention 45 and the advantages and merits thereof, reference is to be had to the following description and the accompanying drawings, wherein is illustrated the preferred form of my invention, in which;

50 Figure 1 is a top plan.

Fig. 2 is a section on the line 2—2 of Fig. 1.

Fig. 3 is a plan of the blank from which the pan is formed.

55 Fig. 4 is a section on the line 4—4 of Fig. 1.

Referring to the drawing, wherein is illustrated the preferred form of my invention, and in which like numerals of reference indicate corresponding parts throughout the several views, and more particularly to Fig. 3 which illustrates the blank from which the pan is constructed it will be noted that the blank is slotted and cut-out in certain portions to form the various parts 60 of the pan. The main portion 1 has the straight front edge 2 which forms the edge of the blade 3. The side edges of the main portion, are cut at right angles to the front edge of the blank. The blank is also provided with the slits 4 adjacent each side edge and it is to be noted that these slits, for the greater portion of their length, are substantially V-shaped. The slits terminate at a point about on the longitudinal center line 75 of the blank of the main portion 1 and from these terminals the sides or marginal portions 5 are adapted to be bent, on the dotted lines 6 for forming the side flanges 7 of the pan shown in the assembled views 1, 2 80 and 4. The marginal edges of these flanges 7 are adapted to be rolled and braced in a manner that will be hereinafter more fully described.

The main portion 1 of the blank is adapted to be folded on the dotted line 8 which indicates a straight line between the terminals of the slits 4 and which is substantially the longitudinal center of the main portion of the blank 1 but which will, in reality, 90 form a transversely extending ridge 9 on the completed pan. A rearwardly extending portion 10 forms a part of the blank and extends beyond the terminals of the side portions 5. The end marginal edge of the 95 portion 10 is separated from the rear terminals of the portions 5 by the slits 4. Two inwardly extending slits 11 are provided which communicate with the slits 4 and the blank is to be bent on the dotted line 12', 100 indicating a straight line between the terminals of the slits 11, for forming the bottom 12 of the dirt receiving receptacle. When thus folded the extension 10 forms the rear wall 13 of the receptacle. This rear 105 wall 13 is disposed at an angle.

The marginal edge of the extension 10 is bent on the line indicated at 14 to form the back wall 14' of the pan and the ends of this wall are overlapped by the tongues 15 110 formed on the terminals of the side portions 5. For forming these tongues the side por-

tions are notched at their ends as shown at 16. This permits the marginal edges of the side portions 5 to be rolled without interfering with the tongues 15 which will be bent 5 at right angles to extend around the rear surface of the back 14.

The dotted lines 17 indicate the straight lines extending from the terminals of the slits 11 to the terminals of the slits 4 and 10 upon which the blank is bent to provide the sides 18 of the receptacle. When thus bent, the corners of the extension 10 formed by the slits 4 and 11, can be bent under the sides 18 to provide the attaching flanges 19 15 which are provided with suitable openings adapted to register with the openings in the sides 18 for receiving a rivet thus holding these portions of the pan tightly together. It is pointed out that these are the only two 20 fastening elements used in the construction of the pan.

When the pan is folded as above described, the marginal edges of the side portions 5 which comprise the flanges 7 of the 25 pan and the marginal edge of the extension 10 which forms the back portion of the pan, may be rolled over a suitable binding rod 20 the terminals of which are placed at the forward edge of the pan. A notch 21 is provided in the back 14 and at this point the binding rod or reinforcing wire 20 is twisted and extended rearwardly to provide the handle 22.

In use, the pan will be held in the position shown by Fig. 4 and the dirt and dust 35 may be swept up over the blade 3 and deposited in the receptacle embraced by the walls 12, 18 and 18. The dirt will not fall or slide out of the pan as is done in the pans 40 now commonly in use. It is to be observed that when the blank is folded for forming the pan the slit 4 is widened until the relatively large opening 23 is provided between the marginal edge of each wall 18 and the 45 adjacent wall of the flange 7. Now, when the pan is slightly tilted edgewise the dirt will be lodged in the corner of the receptacle at one end thereof and may be dumped out of the receptacle through the opening 23. 50 By virtue of the size of the opening and the angular disposition of the corresponding wall 18, the dirt will be concentrated at this point so that it will not spread out and cover surrounding articles when the dirt is being 55 ejected.

From the foregoing it will be observed that a very simple and durable dust pan has been provided, the details of which embody the preferred form. I desire it to be under-

stood however, that slight changes in the 60 minor details of construction may be made without departing from the spirit of the invention or the scope of the claims hereunto appended.

I claim:

1. A dust pan comprising a front blade and a receptacle carried at the rear thereof, the meeting portions of the said blade and the receptacle providing a ridge transversely across the pan, side flanges integrally connected to the blade and extending rearwardly and upwardly above the said receptacle at each end thereof whereby openings are provided at each end of the said receptacle, the rear wall of the receptacle having 70 its marginal edge rolled and contacting with the ends of the said flanges, the marginal edges of the said flanges also being rolled.

2. A dust pan comprising a front blade and a receptacle carried at the rear thereof, 80 the meeting portions of the said blade and the receptacle providing a ridge transversely across the pan, side flanges integrally connected to the blade and extending rearwardly and upwardly above the said receptacle at each end thereof whereby openings are provided at each end of the said receptacle, the rear wall of the receptacle having 85 its marginal edge rolled and contacting with the ends of the said flanges, the marginal edges of the said flanges also being rolled, 90 and a brace wire received by the said rolled edges of the flanges and the said wall.

3. A dust pan comprising a front blade and a receptacle carried at the rear thereof, 95 the meeting portions of the said blade and the receptacle providing a ridge transversely across the pan, side flanges integrally connected to the blade and extending rearwardly and upwardly above the said receptacle at each end thereof whereby openings are provided at each end of the said receptacle, the rear wall of the receptacle having 100 its marginal edge rolled and contacting with the ends of the said flanges, the marginal edges of the said flanges also being rolled, 105 a brace wire received by the said rolled edges of the flanges and the said wall, the margin of the said rear wall being notched whereby the said wire may be twisted, and a handle 110 projecting rearwardly from the said notch.

In testimony whereof I affix my signature in presence of two witnesses.

FERDINAND O. SPAULDING.
